VIOLIN

Ignatz Kohn, New York, N. Y.

Application February 19, 1949, Serial No. 971

Term of patent 14 years

(Cl. D56—10)

To all whom it may concern:

Be it known that I, Ignatz Kohn, a citizen of the United States, residing at New York, in the county of New York and State of New York, have invented a new, original, and ornamental Design for a Violin, of which the following is a specification, reference being had to the accompanying drawing, forming a part thereof.

In the drawing:

Fig. 1 is a perspective view of a violin, showing my new design;

Fig. 2 is a side elevational view of the same;

Fig. 3 is a front elevational view of the same;

Fig. 4 is an end elevational view;

Fig. 5 is a top plan view; and

Fig. 6 is a bottom plan view of the same.

I claim:

The ornamental design for a violin, as shown.
IGNATZ KOHN.
